UNITED STATES PATENT OFFICE.

CHAUNCEY W. GAY, OF WEST SPRINGFIELD, MASSACHUSETTS.

FEEDING MECHANISM.

SPECIFICATION forming part of Letters Patent No. 726,819, dated April 28, 1903.

Application filed March 25, 1901. Serial No. 52,821. (No model.)

To all whom it may concern:

Be it known that I, CHAUNCEY W. GAY, a citizen of the United States of America, and a resident of West Springfield, in the county 5 of Hampden and State of Massachusetts, have invented certain new and useful Improvements in Feeding Mechanism, of which the following is a full, clear, and exact description.

This invention relates to improvements in feeding mechanism applicable for employment in various kinds of machinery.

The invention is particularly applicable, for instance, in a machine such as illustrated and described in Letters Patent of the United 15 States issued to me March 27, 1900, No. 645,950, which comprises mechanism for intermittently feeding forward the cardboard or strip from a roll or supply thereof to and subject to the action of creasing, scoring, and 20 severing mechanism by means of which blanks for the production of paper boxes are produced. In such a machine the intermittent rotational movements imparted in longer or shorter extents to a ratchet-wheel from the 25 rocking reciprocatory motion of a pawl-carrier is transmitted through suitable mediums of connection to the positive feed-rolls for carrying the stock forward through the machine for each blank-making operation there- 30 of. Inasmuch as it is desirable that the feed motions shall be positive and each succeeding one uniform in extent with that of the preceding, so that the blanks shall all be made of exactly the same length, it has been 35 found necessary to provide a device which is more positive, certain, and uniform in action than the well-known pawl and ratchet here- 40 tofore commonly used and one in which there can be no such mode of action as in the ordinary pawl-and-ratchet feed mechanism as to result in the forcible thrust of the pawl for driving the ratchet-wheel, stripping the teeth of the ratchet-wheel, which teeth must be nec- 45 essarily small and delicate in many cases in order to acquire a finely adjusted or regu- 50 lated propulsive motion of the ratchet-wheel; and in order to acquire a feed mechanism which shall have the positive advantages hereinabove indicated as highly desirable and advantageous and which shall be devoid of the objectionable characteristics above noted I provide, in combination with the wheel,

preferably a finely-toothed ratchet-wheel, to which the intermittent rotational propulsive movement is to be imparted, a swinging reciprocatory or oscillating pawl-carrier, a portion of which has its location adjacent and radially beyond the toothed rim of the wheel and which latter portion is equipped with a pawl which has bearing or engagement members arranged to embrace the thickness of the rim of the wheel and in the working motion of the pawl-carrier to have relatively to the latter a slight degree of swinging motion, whereby to firmly grip and bind the rim of the wheel, so that the wheel must necessarily move positively in unison with the pawl-carrier, the said capability for the swinging motion of the pawl relatively to its carrier on the reversed motion of the carrier enabling the pawl to pass freely back about the rim of the wheel to assume its position for a new gripping and binding for the succeeding propulsive thrust.

The invention preferably contemplates a duplicated provision of the novel pawls and the peculiar supports therefor on the pawl-carrier, whereby the strains and effective grippings upon the wheel to be propelled are balanced and distributed, inuring to greater 80 positiveness and ease of action and a lessened tendency to impairment or wearing out of those operative parts of the mechanism on which are imposed the brunt of the work.

The invention consists in the particular construction and combination or arrangement of parts, all substantially as hereinafter fully described, and set forth in the claims.

The present improved feed mechanism is illustrated in the accompanying drawings, in which—

Figure 1 is an elevation with a part of the pawl-carrier and one of the gripping-pawls shown in section. This view represents the pawls as being in their working engagements to drive the ratchet-wheel. Fig. 2 is a view of a part of the mechanism shown in partial elevation and partial section to indicate the mode of free reversed movement of the pawl without effect upon the ratchet-wheel. Fig. 3 is a perspective view of the pawl-carrier having the duplicate grooves or sockets for the pair of pawls, one thereof being omitted, and showing a portion of the toothed rim of

the wheel, these parts being seen as at the opposite side from that represented in Fig. 1. Fig. 4 is a perspective view of one of the pawls.

5 Similar characters of reference indicate corresponding parts in all of the views.

In the drawings, C represents a wheel which is understood as the propulsion-wheel of the feed mechanism, the same being fixed on the 10 shaft D and provided with the annular flange or rim E, exteriorly provided with the series of comparatively fine ratchet-teeth d.

B represents the pawl-carrier, constructed in the form of a centrally-hubbed bar loosely 15 mounted on the shaft D alongside the ratchet-wheel C, the opposite arms or members thereof being extended radially beyond the opposite sides of the wheel and widened, as indicated at f f, to extend across and adjacent 20 the toothed peripheral opposite portions of the wheel.

The pawl-carrier B has its rocking reciprocatory motion imparted thereto by the connecting rod or link g, pivotally connected to 25 the pawl-carrier and to the radially-adjustable slide-block h, carried by the grooved disk b, fixed on the driving-shaft A of the mechanism. By turning the screw i to adjust the point of connection j nearer or farther 30 from the center of the shaft A the throw or sweep of the pawl-carrier will be correspondingly modified.

The thickened portion of the pawl-carrier, which is adjacent and in overlapping relation 35 outside of the rim-flange of the wheel C, has the groove or socket m therein for the gripping or clutching pawl G. The said socket or groove for the pawl has its direction across the said offset and widened portion of the 40 pawl-carrier, in which it is formed angularly to the radial line of the pawl-carrier and which line is tangential to a circle between the rim and axis of the wheel C.

The pawl G is in the form of a plate or flat 45 block, having intermediate its ends the recess n, which is extended from one edge transversely toward the other, whereby the pawl is made to comprise opposite end members o o² to occupy positions at the outer and inner 50 surfaces of the rim-flange of the ratchet-wheel and the uniting-back p. The thickness of the pawl is slightly less than the width of the groove or pawl-socket m, so that there may be two motions permitted to the pawl— 55 that is, a sliding motion of the pawl in the direction of its length and a slight degree of tilting or rocking motion of the pawl in a direction across the thickness thereof.

In practice the difference between the 60 thickness of the pawl and the width of the groove m is quite small, although sufficient for efficiency of action, and in the illustration here given the excess of the thickness of the groove over that of the pawl is somewhat exaggerated.

The spring q is applied for draft on the inner end of the pawl in a direction to move the

latter inwardly and also to tilt it, so as to have normally about the relations indicated in Fig. 1 relatively to the inner and outer portions of the wheel-rim and the sides of the groove m.

As a convenient means for the application of the spring the pawl-carrier has an arm or rod t extended transversely of its radial 75 length, to the outer hooked end of which one end of the spiral spring is interlocked, the other end of the spring having connection with the inner end of the pawl.

When the pawl-carrier has its sweep to assume a position for the new working stroke, the binding or gripping of the embracing-pawl about the rim-flange of the wheel is freed and the toothed or engagement end u of the outer member o of the pawl clicks or rides 85 freely over the outer surface of the rim, while the engagement portion u² of the inner pawl member o² rides freely over the inner surface of the rim. Now on the reversed direction when the pawl-carrier has its working sweep 90 in the direction of the arrow at the right of Fig. 1 the tooth or working end u of the pawl coming into engagement with the ratchet-teeth of the wheel constitutes a fulcrum, so that the pawl may be rocked from the point 95 v of engagement to bring also the portion of the pawl member o² firmly against the inner surface of the rim, this binding or gripping being in part insured by the direction of the strain of the spring q, but more positively 100 and forcibly by the direction of the arc course of the swing of the pawl-carrier and pawl relatively to the radial length of the pawl-carrier and to the angular direction of the length of the pawl to said radial length.

While it will be apparent that the pawl-carrier having a single arm and constructed to carry and equipped with but a single pawl arranged for operation as described constitutes an entirely operative and extremely desirable feeding-clutch, the duplication, as 110 shown, is greatly to be preferred, as manifest, for the reasons that the strains are distributed, and consequently divided, and that there will be a liability of a lessened lost motion on the 115 working thrusts.

While I am not to be absolutely limited to the employment of the rim-flange of the wheel externally ratchet-toothed, as shown, for the device will be fairly effectual with 120 both inner and outer surfaces of the rim plain, the provision of the ratchets is preferred as tending to increased positiveness of action.

Having thus described my invention, what I claim, and desire to secure by Letters Patent, is—

1. In a feeding device, the combination with the flange-rimmed wheel, to which rotational movement is to be intermittently imparted, of a pawl-carrier having back-and-forth swinging motions, a portion of which carrier has its location outside of the rim of the wheel, and is provided with a pawl socket or groove, the direction of the length of which is angular to

radial line of the wheel intersecting said grooved portion of the carrier, means for imparting the back-and-forth motion to the carrier, and the pawl having the opposite portions o and o^2 to embrace the rim, one of said portions having a supporting engagement in the said pawl-socket, and having its thickness slightly less than the width of the socket whereby it may have both an endwise play in 5 the aforesaid angular line and a swinging motion relatively to said angular line and a spring normally acting to slide said pawl to cause the rim-embracing portions thereof to engage the rim of the wheel, substantially as 10 described.

2. In a feeding device, the combination with the flange-rimmed wheel, to which rotational movement is to be intermittently imparted, of a pawl-carrier having back-and-forth swinging motions, a portion of which carrier has its location outside of the rim of the wheel, and is provided with a pawl socket or groove, the direction of the length of which is angular to radial line of the wheel intersecting said 20 grooved portion of the carrier, means for imparting the back-and-forth motion to the carrier, and the pawl having the opposite portions o and o^2 to embrace the rim, one of said portions having a supporting engagement in 25 the said pawl-socket, and having its thickness slightly less than the width of the socket, whereby it may have both an endwise play in the aforesaid angular line and a swinging motion relatively to said angular line, and the 30 spring engaged at the inner end of the pawl, and operating to draw the latter endwise and to rock it relatively to its carrier, substantially as described.

3. In a feeding device, the combination with 35 the flange-rimmed wheel externally toothed, of a pawl-carrier mounted on the shaft of said wheel and radially extended outside of the rim of the wheel, and constructed with the

widened portion f provided with a pawl-groove m , the direction of the length of which 45 is angular to the radial length of the pawl-carrier, means for imparting the back-and-forth motion to the carrier, and the pawl having the opposite portions o and o^2 to embrace the rim, one of said portions having a supporting engagement in the said pawl-groove, and having its thickness slightly less than the width of the groove, whereby it may have 50 an endwise play in the line of its length, and a swinging motion across its length, and the 55 spring q applied as described.

4. In a feeding device, the combination with the shaft D having the flange-rimmed externally-toothed wheel C , loosely mounted thereon, of the pawl-carrier B , the same consisting 60 of a bar centrally and loosely mounted on the shaft, having the opposite arms radially extended beyond the rim of the wheel and having the widened portions ff which are offset and overlapped across the opposite external 65 peripheral portions of the rim, and are constructed with the grooves $m m$ which are angular to the radial length of the pawl-carrier arms, and said pawl-carrier having the extension members tt , the pawls $G G$ each comprising separated engagement members o and o^2 and the uniting-back p , and each said pawl having its member o mounted within the groove m therefor in the carrier and having a thickness slightly less than the width of the 70 groove, and the springs $q q$ applied between the outer ends of the said rods t and the inner ends of the pawls, all substantially as and for the purposes set forth.

Signed by me at Springfield, Massachusetts, 80 this 15th day of March, 1901.
